UNITED STATES PATENT OFFICE.

OSCAR SCHULZE, OF ST. LOUIS, MISSOURI.

IMPROVEMENT IN MUSIC-STANDS.

Specification forming part of Letters Patent No. **140,547**, dated July 1, 1873; application filed June 4, 1873.

To all whom it may concern:

Be it known that I, OSCAR SCHULZE, of St. Louis, St. Louis county, Missouri, have invented a certain Improvement in Portable Music-Stands, of which the following is a specification:

My invention consists of a music-stand which is adjustable in height, and which is made to collapse into a compact form of small dimensions, for transportation; the supporting-standard consisting of an arrangement on the "lazy-tongs" principle, and the base and book-support or top frame being expanded automatically by the extension of the standard.

In the drawings, Figure 1 is a perspective view of my improvement in extended condition, fit for use. Fig. 2 is a perspective view in closed condition, arranged for transportation.

The base has two end pieces, A, to which are hinged at *b* side pieces B, having hinges *b'* at their middle. To each of the end pieces A is attached a sliding foot or steady-bar, C, whose end *c* passes through the other end piece A. This arrangement of the base is to allow its expansion at both sides and ends as the lazy-tongs standard is extended vertically, as shown in Fig. 1. The extensible standard D is formed on what is known as the lazy-tongs principle—that is, a number of bars, *d*, pivoted together at the ends and middle, as shown—so that the standard may be extended and contracted in a straight line. The lower pair of bars, *d*, are hinged to the end pieces A at *a*, and the bars *d* are hinged to the end pieces E of the head or book-rest frame. These end pieces have side bars *e*, which slide together in straps *e'*, so as to allow the ends E to approach each other or recede in the same manner as the ends A of the base. Hinged to the end pieces E are blocks F, having sliding bars *f*, similar to those *e*, and op-

erating in a similar manner. Pivoted to the blocks F at *f* are bars *d'*, similar to those *d*, and at their lower ends are pins *g*, traversing slots *h* in the horizontal bars H, to which the bar I is hinged at *i*. K are brace-rods, hinged to the bars *d'* at *k'*, and to the bars *d* at *k*, so that, as the standard D is drawn upward, the ends *k* are drawn toward each other, and the braces force outward the lower edges H I of the book-rest frame.

The operation is as follows: Supposing the stand to be in its closed condition, as shown in Fig. 2, the pieces E are grasped, and by giving a quick upward motion to the hands the standard is extended to some distance. The foot may be then placed upon the base and the book-rest frame drawn up to the desired height. As the standard is extended, its lower bars or levers *d* draw in the end pieces A of the base, and extend its bearing area, (at the sides by means of the side pieces B, and at the ends by the outwardly-sliding bars C,) as shown in Fig. 2. At the same time, the lower edges H I of the book-rest frame are forced outward by the brace-bars K, and the foot-rest I of the book being then turned outward the stand is ready for use.

To close it up, it is only necessary to fold in the foot-rest I and force the head downward, when the parts automatically assume the position shown in Fig. 2, in which the whole is contained in a small space, and may be easily transported without liability to injury.

I claim as my invention—

The combination of expanding base A B C, extension-standard composed of bars *d*, and automatically-opening book-rest frame E F H I, substantially as set forth.

OSCAR SCHULZE.
